UNITED STATES PATENT OFFICE.

FRANK BERNDT, OF GALVESTON, TEXAS.

ELEVATING AND LOADING DEVICE.

Application filed April 18, 1922. Serial No. 555,456.

To all whom it may concern:

Be it known that I, FRANK BERNDT, citizen of the United States, residing at Galveston, in the county of Galveston and State 5 of Texas, have invented certain new and useful Improvements in an Elevating and Loading Device, of which the following is a specification.

This invention relates to new and useful 10 improvements in an elevating and loading device.

One object of the invention is to provide a device of the character described which is designed for facilitating the handling 15 of heavy objects in transferring them from one place to another and is more especially designed for use on wharves for loading ships and water craft, although the device is adapted to be used for general purposes.

Another object of the invention is to provide a device of the character described having a vertically adjustable frame work providing for the transfer of objects from one 25 location to other locations of different elevations.

With the above and other objects in view the invention has particular relation to certain novel features of construction, operation 30 and arrangement of parts, an example of which is given in this specification and illustrated in the accompanying drawings, wherein:—

Figure 1 is a side elevation of the device 35 partially broken away.

Figure 2 is a front view partially broken away and shown partly in section.

Figure 3 is a plan view of a conveyor chute employed and,

Figure 4 is a side view thereof partially broken away and partly in section.

Referring now more particularly to the drawings wherein like numerals of reference 45 designate similar parts in each of the figures, the numeral 1 designates a supporting frame work, taken as a whole, and consisting of suitable upright beams and cross braces anchoring said beams together. This frame work is mounted on suitable rollers 2, 2 providing for its movement from place to place. Above the frame work there

is a substantially rectangular frame 3 which is carried by the upper ends of the upright posts 4. These posts work through the corresponding bearings 5 which are provided at the top of the frame work, and the lower ends telescope into aligned cylinders 6, at the bottom of the frame work. Depending from the frame on each side are the rack members 7, 7 which mesh with the spur gear wheels 8, 8. These gear wheels are fixed on the transverse shaft 9 which is rotatably mounted in suitable transversely aligned bearings formed in the framework, and the ends of the shaft 9 have the cranks 10, 10, by means of which the shaft and gear wheels may be turned and the rack members 7, and the frame carried thereby adjusted up or down. These rack members are held at any point of adjustment by means of suitable dogs as 11, which are pivoted to the framework and are disposed to be engaged with the gear wheels 8 to lock them against rotation. At the bottom of the framework there is a transverse shaft 12 which is geared to and driven by a suitable motor 13, and mounted in suitable bearings upon the frame 3 there is a transverse shaft 14. The shafts 12 and 14 have aligned sprocket wheels 15, 15 and 16, 16 spaced apart and operating over them are the respective sprocket chains 17, 17. These sprocket chains carry a jointed belt 18 whose upper surface is provided with the cleats 19 which are spaced apart.

The objects to be transferred are placed upon said belt 18 which travels in the direction indicated by the arrow in Figure 1 and the cleats engage with said objects and elevate them and deliver them into the declining chute 20, by means of which they are delivered from the elevator into the boat or other receiver. The upper end of the chute has the eyes 21, 21 adapted to engage with the side hooks as 22, 22 carried by the frame 2 and the chute is thus supported in position. As merchandise or other objects are delivered they are usually placed in stacks, and as the stacks become higher it is necessary to elevate the chute in order to make delivery at the proper place and it is further necessary to elevate the framework 3,

so that the receiving end of the chute will be high enough to give it sufficient declination. In order to do this additional links are added to the chain 17, and additional 5 sections are added to the belt 18 and the dogs 11, are disengaged and the cranks 10 turned, which will operate from the mechanism described to elevate the frame 3 and the receiving end of the chute 20. It is obvious that 10 said frame and chute may be lowered by a reverse operation.

In Figures 3 and 4 I have shown a chute having a double discharge end and provided with a transfer gate whereby the objects being delivered will be delivered at different places alternately. As stated the chute separates into two discharges 23, 23, which as shown are formed of telescoping sections providing for variations in the length of the 20 chute. This chute has a vertical transfer gate 24 pivoted at the point 25 and having its free end toward oncoming objects passing along the chute. Each branch 23 of the chute has a wing 26 hinged to the bottom 25 thereof and extending transversely with respect thereto. Attached to the free end of each wing there is a cable 27, each cable passing around a suitable pulley as 28 mounted in the side of the chute, and being 30 attached at its other end to the free end of the transfer gate 24. When an object passes down one branch 23 of the chute it will depress the upstanding wing 26 thereof and pass on over it and this will operate through 35 the corresponding cable 27 to swing said gate across the chute, into the position shown in dotted lines in Figure 3 and close the branch along which the object has just passed and the next oncoming object will 40 pass down the other branch of the chute and, through the mechanism described, will swing said gate back into the position shown in full lines in Figure 4. Through this mechanism the objects being delivered will be delivered 45 one at the time alternately through branches 23 of the chute and discharged at different places thus giving more room to the workmen handling the delivered objects.

What I claim is:—

- 50 1. A device of the character described including a supporting frame work consisting of upright beams and cross braces anchoring the beams together, a substantially rectangular frame above the frame work, upright posts to the upper ends of which the frame is secured, bearings at the top of the frame work through which the posts work, cylinders carried by the frame work into which the lower ends of the posts telescope, rack members depending from the frame, a transverse rotatable shaft carried by the frame work, gear wheels fixed on said shaft and in mesh with said rack members, means for rotating the shaft to adjust the frame up or down, means arranged to engage with said gear wheels to lock them against rotation 105 and to thus hold the frame at any desired point of adjustment, an endless apron forming an elevator, means carried by the frame work and frame respectively around which the apron revolves, a motor in operative connection with said means and driving the same to revolve said apron, spaced cleats carried by the outer surface of said apron. 110
- 55 2. A device of the character described including a supporting frame work consisting of upright beams and cross braces anchoring the beams together, a substantially rectangular frame above the frame work, upright posts to the upper ends of which the frame is secured, bearings at the top of the frame work through which the posts work, cylinders carried by the frame work into which the lower ends of the posts telescope, rack members depending from the frame, a transverse rotatable shaft carried by the frame work, gear wheels fixed on said shaft and in mesh with said rack members, means for rotating the shaft to adjust the frame up or down, means arranged to engage with said gear wheels to lock them against rotation 115 and to thus hold the frame at any desired point of adjustment, an endless apron forming an elevator, means carried by the frame work and frame respectively around which the apron revolves, a motor in operative connection with said means and driving the same to revolve said apron, spaced cleats carried by the outer surface of said apron. 120
- 60 3. A device of the character described including a supporting frame work consisting of upright beams and cross braces anchoring the beams together, a substantially rectangular frame above the frame work, upright posts to the upper ends of which the frame is secured, bearings at the top of the frame work through which the posts work, cylinders carried by the frame work into which the lower ends of the posts telescope, rack members depending from the frame, a transverse rotatable shaft carried by the frame work, gear wheels fixed on said shaft and in mesh with said rack members, means for rotating the shaft to adjust the frame up or down, means arranged to engage with said gear wheels to lock them against rotation 125 and to thus hold the frame at any desired point of adjustment, an endless apron forming an elevator, means carried by the frame work and frame respectively around which the apron revolves, a motor in operative connection with said means and driving the same to revolve said apron, spaced cleats carried by the outer surface of said apron, a declining delivery chute whose upper end is positioned to receive the loads elevated by and 130

delivered from said apron, the discharge end of said chute being divided into a plurality of branches, and means carried by said chute and arranged to be actuated by the 5 loads being discharged therealong, and arranged to discharge said loads through said branches alternatively.

In testimony whereof I have signed my name to this specification in the presence of two subscribing witnesses.

FRANK BERNDT.
